[57] **CLAIM**

The ornamental design for a Florida fishing tape, as shown and described.

DESCRIPTION

FIG. 1 is a top view of the "Florida fishing tape" showing the design;

FIG. 2 is a view from the bottom thereof;

FIG. 3 is a side view (either left or right) thereof;

FIG. 4 is an end view from the front thereof; and,

FIG. 5 is an end view from the rear thereof.

1 Claim, 2 Drawing Sheets

FIG. 1
